UNITED STATES PATENT OFFICE

JOSEPH CONN DAWSON, OF LONDON, ENGLAND, ASSIGNOR TO THE CLEVELAND FOLDING MACHINE COMPANY, OF CLEVELAND, OHIO, A CORPORATION OF OHIO

FOLDING MACHINE

Application filed June 18, 1927, Serial No. 199,673, and in Great Britain July 2, 1926.

This invention relates to paper or the like sheet-folding machines and has for its object to provide a folding machine capable of folding one sheet into two or more separate signatures and delivering each signature separately by the same unit, for such as circular and book work as well as other folding work. For example, two or more 8-page right-angle pamphlets, two or more 32-page right-angle 5 signatures or other combination of folds such as two 16-pages, can be folded and cut and each section delivered separately.

In the known machines of this type it is the common practice for producing, say, two 15 16-page booklets to print single sheets with two signatures up and after a guillotine operation to cause each half of the divided sheet to be folded in a separate folding unit of the machine as a single sixteen page, the separate 20 sixteen page signatures being then delivered separately through their individual units.

Now by means of the arrangement according to this invention a full size sheet printed two signatures up can be folded, cut and the 25 separate signatures delivered through one and the same unit thus saving the preceding guillotine operation and dispensing with the necessity of separate units for the folding and delivery of the separate sheets. By this 30 method therefore the production or capacity of the machine is practically doubled, while at the same time although larger sheets are handled the readjustments necessary when treating cut sheets are not required as the 35 original printer's lay edges are maintained.

In order to attain this object according to one form of this invention a differential speed is applied at the point of the feed where the sheet is subjected to the action of the usual 40 slitting or cutting tools so that at the moment of cutting two different speeds are applied respectively to the individual sheets thus severed from the single sheets and these individual sheets then travel one after the other 45 through the same folding device for individual folding. This differential speed may be attained by, say, the interposition in the gear train of the sheet feeding mechanism of a retarding gear so as to produce a dwell on the rear portion of the single sheet while main-

taining the normal feed speed on the advanced portion thereof just as the rotary cutter or slitter comes into action; or by dividing the whole gear train into a slower and a faster driving section the difference of speed, 55 in either case, aiding, as will be understood, in the quick separation of the cut sheets and, therefore, in a cleaner cut at the requisite point.

The invention is herein disclosed as applied to a folding machine of the type shown in United States Patent No. 1,273,609 to Reuben Hitchcock, dated July 23, 1918, where a train of pinions is provided to drive fibre rollers (a well known method of driving a sheet into the base of a cross-carrier before entering the folding rolls), these fibre rollers are in two sections, the transmission of drive between the sections being obtained by belt and pulley or its equivalent. By interposing a retarding gear at the point at which in this arrangement the rotary slitter is used, the rearward section of the fibre feed rolls is driven at a reduced speed relative to the section in advance thereof and consequently at the moment the sheet is divided its advanced portion moves on while the succeeding portion is retarded in its progress through the machine thereby providing sufficient clearance between the two sheet portions enabling them to follow one another through the same folding device and to be folded, as required, separately and yet in one and the same folding unit.

In the accompanying drawings:—

Fig. 1 is a side elevation of a complete folding machine of the buckle type, except for the omission of the last feed table and fold section.

Fig. 2 is a similar view on a larger scale of that part of the machine to which, in this instance, the invention is applied.

The machine chosen to illustrate the performance of the invention is of the paper buckling type in which several so-called parallel or legal folds and folds transverse thereto may be made in any required succession. For its initial operation it comprises a set of feed and folding rolls A, B, C and D and two buckling plates f^1 and f^2 with their

respective adjustable stops g' and g^2 , generally known in the art, paper being fed to rolls A, B from a feed table M through feed rolls N, N and guide plates O, O, Fig. 1.

5 A full sized sheet, printed two signatures up for 32 pages each, may be fed along the table M through feed rolls N, N and guide plates O, O into the first parallel fold section, which comprises rolls A, B, C, D and fold plates f' and f^2 . This fold section, when operated at capacity, imparts two parallel folds to the sheet, thereby making four leaves. The sheet thus folded is then carried downwardly on edge and shifted transversely 10 in an edgewise direction into the second or cross fold section, comprising a fold plate f^3 with its adjustable stop g^3 and fold rolls, only two of the latter, E, G, appearing in the drawing. In this fold section one trans- 15 verse fold is imparted to the sheet, which then becomes an eight leaf or eight fold sheet. This sheet is then fed on edge between a pair of slitter rolls L provided with slitter knives h and feeding wheels w. The sheet is thereby 20 cut along the line d (Fig. 2) in the usual manner into two parts or signatures s' , s^2 which are caused to travel still on edge, but at right angles to the previous travel of the sheet, across a down feed frame k, and these parts 25 are then fed downwardly thereon by a series of small fibre or like feed rollers i and i' to a pair of horizontal feed rolls H, J, by means of which the travel of the folded parts is changed to a horizontal plane. The driving 30 arrangement on this down feed frame is in this instance shown associated with a particular form of the present invention.

The side bar p which carries the bearings for the rollers i, i' is rigidly supported by a 35 sleeve q which is adjustable along a horizontal guide rod r and is slotted and provided with a clamp v by means of which it may be secured in adjusted position. The width of the frame may thus be varied so as to adapt 40 it to fold sheets of varying dimensions, it being necessary that the sheets be grasped by the rollers i, i' before the sheets are released from the action of feeding wheels w on the 45 shafts carrying the slitting knives h.

50 In the known arrangement chosen to explain the performance of this invention all of the small feed rollers i, i' are rotated at a uniform speed commensurate with the speed of travel of the signature through the preceding folding operations, so that the two 55 signature portions s' , s^2 even if cut apart at d (Fig. 4) would still travel on as one without being properly separated one from the other.

60 According now to the invention these rollers are arranged in two groups comprising the rollers i and i' respectively. The lower group, that is the leading group in the direction of travel, comprising the rollers i is 65 geared to run at normal speed, taking its

drive from the machine where convenient, as for instance from roll H, while the rear or upper group comprising the rollers i' is rotated at a reduced speed, thus feeding the upper signature s^2 at a lower speed in relation to the feed speed of the signature s' and creating a dwell resulting in a local separation of the two signatures. This reduction of speed is preferably effected by the interposition between the two groups of rollers i , i' of a reducing gear such for example as shown in the drawings. This gear comprises a belt l and pulleys m and m' . It will be clear that in consequence of this arrangement the preceding or lower signature s' in advancing outruns the upper signature s^2 which lags behind so that a space or interval is created between them as shown at u in the vertical plane in Fig. 2. In this advance the signature s' reaches a pair of further feed rolls H and J and is conveyed by them on to a suitable horizontal cross carrier, not shown, in a well known way. The signature s' is then moved upon the horizontal cross carrier mentioned into a third fold section, not shown, in which there is imparted to the signature a further fold, producing a signature of 16 leaves or 32 pages. The signature s^2 follows at the interval referred to, after having passed out of the group of rollers i' into the group of rollers i, and it too is also folded in the third fold section into a second 16 leaf, 32 page signature. The two signatures are thus forwarded one behind the other to the final fold section, but at such distances apart as to eliminate any interfolding of the two sections.

It will thus be seen that by means of an arrangement of the kind described the capacity of a folding machine dealing with full sized sheets printed two signatures up can be readily doubled without involving any material increase of cost, the arrangement used for that purpose being, as clearly shown, a simple attachment capable of being quickly fitted when required and detached when not wanted without detriment to the normal arrangement or working of the machine itself.

It will be obvious also that arrangements equivalent to the one specifically described may be readily conceived by those skilled in the art for performing the invention without departing from the spirit thereof.

I claim as my invention:—

1. In a machine of the class described, means for dividing a sheet and moving the divisions thereof side by side onto a cross feed frame, feeding means associated with said cross feed frame, said feeding means being divided into a forward and a rear section, and means for driving the feeding means of the two sections at different speeds.

2. In a machine of the class described, means for dividing a sheet and moving the

divisions thereof side by side onto a cross feed frame, and means for moving the two divisions of the sheet on said cross feed frame in the same direction, said last-named means comprising two sections the forward one of which is geared to run faster than the rear one.

3. In a machine of the class described, means for dividing a sheet and moving the 10 divisions thereof side by side onto a cross feed frame, and means for moving the two divisions of the sheet on said cross feed frame in the same direction, said last-named means comprising two sections the forward one of 15 which is geared to run at a speed corresponding to the speed of the adjacent feeding means, and the rear section of which is retarded with respect to the forward section.

4. In a machine of the class described, 20 means for dividing a sheet and moving the divisions thereof side by side onto a cross feed frame, and means for moving the two divisions of the sheet on said cross feed frame in the same direction, said last-named 25 means comprising two sections the forward one of which is geared to run at a speed commensurate with the speed of the adjacent feeding means, and the rear section of which is driven from the forward section through 30 reducing gearing.

5. In a machine of the class described, means for dividing a sheet, a cross feed frame, means for moving the divisions of 35 said sheet side by side onto said frame, short rollers mounted upon one side bar of said frame for advancing the sheets thereon, said side bar being adjustable transversely of the length of the frame, and means for driving 40 said rollers so as to impart more rapid motion to the forward than to the rearward sheet.

In testimony whereof, I hereunto affix my signature.

JOSEPH CONN DAWSON.
